Leo Stein

Stein & Stein

UNITED STATES PATENT OFFICE

LEO STEIN, OF CHICAGO, ILLINOIS

BRIEF CASE

Application filed July 5, 1927. Serial No. 203,532.

My invention belongs to that general class of devices known as brief cases or the like, and relates more particularly to a brief case or bag for the carrying of papers, documents, books, catalogs, samples or various other articles.

The invention has among its objects the production of a case of the kind described, which is simple, durable, attractive, compact and satisfactory for use wherever found applicable. More particularly it has as an object an improved production which is extremely strong and durable and which is exteriorly attractive. More particularly it relates to an improved handle construction wherein the handle is adjustable to provide for variation in the thickness of the material carried in the bag.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a side view of my improved case;

Fig. 2 is a sectional view taken substantially on line 2—2 of Fig. 1;

Fig. 3 is a top plan view of the same;

Fig. 4 is an under cut sectional view taken substantially on line 4—4 of Fig. 1;

Fig. 5 is a perspective view of the inner bar;

Fig. 6 is a perspective view of one of the spaced outer attaching plates; and

Fig. 7 is a perspective view of the same covered.

The present invention is in the nature of an improvement in the brief case shown in application #683,395.

Referring to the drawings in which an embodiment of the invention is shown, 1 represents the body of the bag of suitable size and material and constructed with any desired number of pockets, as is customary in a bag of this kind. One face is made sufficiently large

to provide a flap 2 which extends over the top of the bag and is generally secured to the front side by a lock 3, or its equivalent. Any style of lock may be employed, but generally one in which several adjustments are possible, the lock itself forming no part of the present invention. There are also provided straps 4—4, which embrace the case and which may be maintained in place by one or more fasteners or slides 4' or their equivalents for the purpose. A handle 5 is provided which is suitably secured to the flap portion 2 so that it may be adjusted laterally to correspond with variations in proportions of the contents of the bag. As shown, 6 is a bar preferably of metal arranged at the inner side of the flap 2 to which are suitably secured spaced outer members 8—8. The members 8 are connected to the plate 6 by suitable means which extend through the slots 2' in the flap and connected to the bar 6. Referring particularly to Figs. 5 and 6, the bar 6 and one of the members 8 are shown. Each of the members 8 is provided with a lug 9 of the size to extend through the slots and into openings 7—7 in the bar 6, the members 8—8 and 6 being preferably covered as hereinafter mentioned. The lugs 9 and openings 7—7 are preferably rectangular or some other shape than circular so that when the lugs project into the slots or openings 7, each member 8 will be prevented from turning. The two lugs 9 are provided with reduced parts 10 which may be headed over as described. As shown, each member 8 is provided with a head 11 having an opening 12 therethrough forming a sleeve for the links 13, which connect each end of the handle with the adjacent member 8. The bar 6 is provided with a covering 14, 15 of leather and the like and each member 8 is provided with a similar covering. As shown, the covering on the members 8 is extended as at 17, 18 and 19, the parts being sewed or stitched together as indicated at 21.

In assembling the device the covered bar 6 is placed on the inner side of the flap and then the members 8 grounded thereon with the lugs 9 extending through the opening 7 on the bar 6. A washer 16, or the like, is arranged over the portion 10 and the portion

10 then headed so that the parts are firmly secured together. It may be mentioned that the lugs 9 are of such height that the parts will be brought in close contact together, but 5 with sufficient pressure between the bars and spaced members 8 that the flap is pinched. This permits adjustment with the parts of the flap, the slots 2' permitting a considerable adjustment one way or the other. It will be noted by referring to Figures 3 and 10 7 that the cover portion 19 of the parts 8 is cut back as indicated at 20. The straps 4 are extended through between the parts 8 and the portion 19 so that these parts form 15 a slide for the straps and locate the straps directly over the slot 2' at either end of the handle so as to conceal the slots. The straps tend to reinforce the lugs 9 or connection between the parts 6 and 8, the greater portion 20 of the load being carried by the straps, this enabling a lighter construction to be employed. The spaced members 8 make the exterior of the case particularly attractive, the reinforcing of the flap being provided 25 for by the use of the bar 6 which prevents the straps from being drawn together at the top when the same is carried at the handle.

Having thus described my invention, it is obvious that various immaterial modifications may be made in the same without departing from the spirit of my invention; hence I do not wish to be understood as limiting myself to the exact form, construction, arrangement and combination of parts 35 herein shown and described, or uses mentioned.

What I claim as new and desire to secure by Letters Patent is:

1. In a device of the class described, a brief 40 case having a cover flap formed with spaced slots, a reinforcing element beneath said flap, spaced reinforcing elements in a line parallel to said first element and disposed upon the outer side of the flap, and means carried by 45 the spaced elements, extending through the slots and engaged with the first element to connect said spaced elements with the first element, said means restraining the spaced elements against pivotal movement relative to the first element.

2. A brief case having a cover flap formed 50 with spaced slots, a bar beneath said flap having rectangular openings, spaced reinforcing members upon the outer side of the flap, rectangular lugs on said members movable in the slots and fitted in the openings in said bar, and reduced portions on said lugs locked to retain said members against pivotal movement relative said bar.

60 3. A brief case having a cover flap formed with spaced slots, a bar beneath the flap, spaced reinforcing members on the flap, projections and sleeves formed on said members, said projections connecting said bar and 65 movable in the slots, cover portions for said

members having strap receiving slots, and a handle connecting said sleeves on said members.

4. A brief case having a cover flap formed with spaced slots, a bar beneath the flap having 70 spaced rectangular openings, spaced reinforcing members on the top of said flap, rectangular lugs on said members movable in the slot and fitted in the openings in the bar, cover portions for said members having 75 strap receiving slots, and a handle having its ends pivotally connected with the ends of said members and forming the sole connection therebetween.

5. A brief case comprising a covered flap 80 having a pair of spaced slots, a bar beneath the flap having rectangular openings in alignment with said slots, a pair of reenforcing members each having an integral rectangular lug passing through one of said 85 slots and the corresponding opening of said bar, means on the ends of said lugs for retaining the members in assembled relation with said flap and said bar, a transverse sleeve in each of said reenforcing members and a handle pivotally secured in said sleeves and forming the sole connection between said 90 reenforcing members, said slots being sufficiently long to permit said handle, reenforcing members and bar to slide transversely of 95 said brief case as a unit.

In testimony whereof, I have hereunto signed my name.

LEO STEIN.
